UNITED STATES PATENT OFFICE.

EVELYN P. SPERRY, OF OAK PARK, ILLINOIS.

FLOOR-SUPPORT FOR BUILDINGS.

No. 823,558.

Specification of Letters Patent.

Patented June 19, 1906.

Application filed September 15, 1905. Serial No. 278,568.

To all whom it may concern:

Be it known that I, EVELYN P. SPERRY, a citizen of the United States, residing at Oak Park, in the county of Cook and State of Illinois, have invented certain new and useful Improvements in Floor-Supports for Buildings, of which the following is a specification.

My invention relates to that class of flooring or floor-supports comprising metallic sleepers or floor-strips embedded in concrete and provided with flanges for holding them in position, such sleepers being formed of side members secured together and adapted to enable the nails of the floor to be driven therebetween and securely held thereby. It relates also to the means for preventing the cracking of the concrete above the metallic floor-beams upon which the sleepers rest.

The principal object of my invention is to provide a simple, economical, and efficient floor-support or flooring for buildings.

A further object of the invention is to provide in a flooring for buildings metallic floor-strips or sleepers adapted to be embedded in and held in place by the concrete and to permit the floor-nails to be driven into and securely held in place thereby.

A further object of the invention is to provide in a floor-support or flooring for buildings suitable means for preventing the cracking of the concrete which is supported by the metallic floor-beams.

Other and further objects of the invention will appear from an examination of the drawings and the following description and claims.

The invention consists in a floor-support or flooring having metallic floor-strips or sleepers embedded in concrete and provided with flanged side members adapted to securely hold the floor-nails, so as to dispense with wooden furring-strips.

It consists, further, in a floor-support having metallic floor-beams provided with metallic floor-strips or sleepers resting thereon and embedded in the concrete and means for preventing the cracking of the concrete by reason of the expansion and contraction of the metallic floor-beams due to variations in temperature.

It consists, further and finally, in the fea-

tures, combinations, and details of construction hereinafter described and claimed.

In the accompanying drawings, Figure 1 is a sectional elevation of a portion of a floor and floor-support constructed in accordance with my improvements; Fig. 2, a view in elevation, taken on line 2 of Fig. 1 looking in the direction of the arrow, and Fig. 3 a detail view showing one of the metallic floor-strips or sleepers to which the floor proper is secured.

In constructing a floor provided with my improvements a plurality of metallic floor-beams *a*, preferably in the form of I-beams, is laid in the ordinary manner in position to support the weight of the flooring members which rest thereon. These I-beams are laid in parallel relation to each other at suitable intervals, and as they are all preferably of identical construction and the manner of laying them is well known it is only deemed necessary to herein illustrate and describe one of such beams.

Metallic floor-strips *b* are arranged at right angles to and rest upon the metallic floor-beams at suitable intervals throughout the entire area of the floor. These metallic floor-beams or sleepers are each formed of a pair of side members secured together by means of rivets *b'*. Bottom flanges *c*, preferably integral with the side members, extend outward laterally therefrom and rest loosely upon the floor-beams. The upper edges of the side members, which form the floor-strips or sleepers, are provided with outwardly and downwardly bent integral portions or flanges *d* in the form of elongated or partially-flattened beads, such flanges extending from end to end of the floor-strips and forming spaces *e* between the outer folds and inner web or side portions.

The floor-strips may be formed in sections the ends of which are secured together by means of metallic rods *f*, as shown in Figs. 1 and 2, which rods extend into the spaces formed by the beads of the joined end portions of the sleepers and securely hold the upper edges thereof in position. The lower edges of the floor-strips are secured by means of U-shaped metallic clips *g*, as shown in Figs. 1 and 3. These metallic clips are mounted

upon the laterally-extending bottom flanges of the strips at the joined end portions thereof and extend across the joint, so as to securely hold them together. The space between the floor-strips or sleepers is filled with concrete *h*, and wherever it is desirable to mount conduits in such concrete, which extends above the bottom of the floor-strips, the floor-strips are cut away, as shown at *i* in Fig. 1, thus permitting the mounting of a conduit *j* in the concrete, as shown. The floor-boards *k* are laid upon the metallic floor-strips or sleepers above described and are also supported in part by the concrete. These boards are secured to the floor-strips or sleepers by means of nails *l*, driven downward, preferably at an incline, between the metallic side members of the floor-strips and securely held in place thereby. The outwardly and downwardly folded integral portions of the metallic side members provide additional rigidity for the floor-strips. Sufficient space is formed between the side members, however, to permit the floor-nails to be driven into securing position between such side members and securely held between the beaded upper edge portions thereof.

In order to provide suitable means for preventing the concrete from cracking at points above the metallic floor-beams, a thin layer of non-adhesive material *m*, preferably paper, is laid upon the upper surface of each of the metallic beams before the concrete is laid. The concrete is then laid and allowed to harden in the usual manner.

By the above arrangement it will be seen that the metallic floor-strips are laid loosely upon the floor-beams and held in place by means of the concrete in which the laterally-extending flange portions of the floor-strips are embedded. The clips which secure the ends of the sections together are also held in place by the concrete and may be riveted to the flanges of the floor-strips, if desired. The upper folds or elongated beads of the floor-strips supply the needed rigidity to securely hold the floor-nails when driven therebetween and, with the rod members *f*, provide means for securing the upper edges of the adjacent end portions together. The rivets which connect the side members of the strips are adapted to permit a sufficient space to be formed between the side members to admit the nails, which are securely held in place, so as to dispense with the necessity of employing wooden furring-strips between the metallic members. By this means a flooring is provided which is entirely fireproof, and the floor-boards are held securely in place.

60 I claim—

1. In a device of the class described, a floor-strip formed of metallic side members pro-

vided with lateral bottom flange portions and having integral outwardly-folded upper portions, and means for securing such side members together in engagement with the opposite sides of floor-nails driven therebetween. 65

2. In a device of the class described, a floor-strip formed of parallel metallic side members provided with lateral bottom flange portions and having integral upper outwardly-folded portions forming longitudinal openings, and means for securing such parallel side members together in engagement with the opposite sides of floor-nails driven there- 70 between. 75

3. In a device of the class described, the combination of a plurality of floor-strips mounted end to end, each formed of parallel metallic side members having upper outwardly-folded portions forming longitudinal openings for receiving a connecting-rod, and a connecting-rod mounted in such openings and connecting the adjacent end portions of such floor-strips. 80 85

4. In a device of the class described, the combination of a plurality of floor-strips mounted end to end, each formed of metallic side members having lateral bottom flanges and upper outwardly-folded portions forming longitudinal openings, connecting-rods mounted in such longitudinal openings and connecting the upper end portions of such floor-strips, and metallic clips mounted upon the bottom flanges and connecting the lower 95 end portions of such strips. 90

5. In a device of the class described, the combination of a plurality of floor-strips mounted end to end, each formed of metallic side members having outwardly-folded upper 100 portions, said side members being secured together and provided with a space therebetween for receiving floor-nails, cement in which such floor-strips are embedded, and means for supporting such floor-strips and 105 the cement in which they are embedded.

6. In a device of the class described, the combination of a plurality of floor-strips, each formed of metallic side members having outwardly-folded upper portions and having lateral bottom flanges, cement in which such laterally-flanged floor-strips are embedded, and metallic floor-beam mechanism upon which such floor-strips are laid for supporting the floor-strips and cement and thereby 110 115 the floor to be laid thereon.

7. In a device of the class described, the combination of a floor-beam, a floor-strip laid thereon formed of metallic side members secured together and having outwardly-folded upper portions and provided with lateral bottom flanges, and a layer of cement in which such laterally-flanged floor-strip is embedded. 120

8. In a device of the class described, the combination of a floor-beam, a floor-strip laid thereon formed of metallic side members, each of such side members being provided with a lateral bottom flange and having an upper folded portion forming a longitudinal opening for receiving connecting-rod mechanism, longitudinally-extending rods mounted in such openings in the side members, me-

tallic clips mounted in engagement with the lateral flanges of the side members, and a layer of cement in which such laterally-flanged floor-strip is embedded.

EVELYN P. SPERRY.
